US00D922340S

(12) **United States Design Patent** (10) **Patent No.:** **US D922,340 S**
(45) **Date of Patent:** **** Jun. 15, 2021**

(54) **RADIATING FIN**

(71) Applicants: **Pai-Ling Kao**, New Taipei (TW);
Dan-Jun Chen, New Taipei (TW);
Guo-Hui Li, New Taipei (TW);
Jun-Chao Liu, New Taipei (TW)

(72) Inventors: **Pai-Ling Kao**, New Taipei (TW);
Dan-Jun Chen, New Taipei (TW);
Guo-Hui Li, New Taipei (TW);
Jun-Chao Liu, New Taipei (TW)

(73) Assignee: **ASIA VITA COMPONENTS CO., LTD.**, New Taipei (TW)

(**) Term: **15 Years**

(21) Appl. No.: **29/712,704**

(22) Filed: **Nov. 11, 2019**

(51) **LOC (13) Cl.** **13-03**

(52) **U.S. Cl.**

USPC **D13/179**

(58) **Field of Classification Search**
